UNITED STATES PATENT OFFICE

PATRICK T. LENNON, OF CLEVELAND, OHIO

ANGULAR BLADE GRINDER

Application filed June 24, 1927. Serial No. 201,061.

This invention relates to mechanism for cutting or grinding multi-bladed cutters, such as reamers and the like.

Reamers are in extensive use in which the cutting edges or blades extend longitudinally of the reamer but are disposed in angular non-parallel relation to the axis thereof. In the formation of reamers of this type it is customary to provide the reamer with an even number of equally spaced cutting edges, inclined at the same angle to a plane normal to the axis of the reamer. While the spacing for the blades or reamers having the same number of blades is the same, the angles at which these blades are disposed varies with different makes, and even in different sized reamers of the same make. This gives rise, in providing an apparatus for forming or sharpening the cutting blades which will provide them with a radial clearance on their outer surface, to many difficulties which do not arise in sharpening reamers having blades parallel to their axes.

By applications of my invention, I am able to use one apparatus for grinding or otherwise sharpening any reamer having inclined blades, irrespective of the angle at which the blades are inclined. The invention will be better understood from the description of one practical embodiment thereof, illustrated in the accompanying drawings, in which:—

Figure 1 is a side elevation of a fixture embodying the invention, parts being shown broken away and in section, designed for use upon a grinder, and

Figure 2 is a transverse view of the apparatus shown in Figure 1 taken on line II—II thereof.

Fig. 3 is a plan view illustrating the relation between the cutter head and blades.

The fixture comprises a bed 1 supported on trunnions 2 of brackets 3 which are bolted or otherwise suitably attached to the table 4 of a grinder. The bed carries a stationary headstock 5 and an adjustable footstock 6, longitudinally aligned therewith, with their axes parallel to that of a grinding wheel 7 carried by the usual mechanism of the grinder. The headstock is provided with a hollow bushing 8, in which the shank of the reamer, or a col-

let, or the like, receiving the shank thereof, may be received and the footstock is provided with an adjustable dead center 9 for supporting the other end thereof. Means, shown in the drawings as a pulley 10, are provided for rotating the bushing in the headstock, and through it the reamer being sharpened. A stationary post 11 is attached to the table of the grinder adjacent the inner end of the footstock and another post 12 is carried by the bed of the fixture or the footstock in transverse alignment with the first mentioned post, the upper ends of the two being connected by a tension spring 13, the tension of which tends to rock the bed and all parts supported thereon toward the grinding wheel.

The fixture is maintained in its normal position away from the grinding wheel by a cam 14 carried by the bushing of the headstock. The cam bears against a rod 15 supported in a manner to be hereinafter described which in turn is supported by a curved shoe 16 adjustably carried by the stationary post, and, therefore, when the rod 15 is interposed between one of the higher portions of the cam and the shoe the headstock is maintained in its normal position, irrespective of whether the portion of the rod interposed between the cam and shoe is in the horizontal plane through the center of the headstock, above, or below this plane. This is essential to produce an accurate cutting edge on the cutter, which shall lie in the surface of a true cylinder, particularly when the blades of the cutter are angularly disposed and the rod is, therefore, inclined so that upon movement of the grinding wheel along the cutter blade sections of the rod in different horizontal planes are interposed between the shoe and cam. The bearing face of the shoe is, when the headstock is in its normal position, concentric therewith.

The ends of the rod 15 are supported in a yoke 17, angularly adjustable as by means of bolts 18 at the upper end of a supporting arm 19 of adjustable length, the bolts passing through slots or large holes in either the yoke or the supporting arm. This arm is pivoted at its lower end upon a rod 20 which is supported in brackets 21 stationary with

respect to the grinding wheel as by being mounted upon the bed or other stationary part of the grinder. The supporting arm may be moved longitudinally along the rod and secured in any position thereon as by split collars 22. The cam has its greatest diameter at points corresponding to the cutting edges of the blades of the reamer, and the diameter decreases immediately beyond these points so that the fixture will be rocked toward the grinding wheel by the spring as soon as the wheel passes beyond the cutting edge of a blade, and will grind the peripheral surface with a radial clearance, preferably in a convex form.

Before the cutting operation is commenced the yoke 17 is adjusted so that the rod is disposed at the same angle to the axis of the reamer as the cutting blades. If, therefore, the reamer is so adjusted that the cam bears against the rod at the cam's maximum radius when the grinding wheel is at the cutting edge of a particular blade, then, as the fixture and grinding wheel are relatively moved longitudinally, the point of contact of the cam and rod is moved circumferentially so that the feed is correctly timed for each point along the blade.

By this means the entire cutting edge of each blade is of the same radial distance from the axis of the reamer and the clearance behind this cutting edge is the same throughout the length of the blade. The apparatus requires no attention after having been adjusted for a given angularity of blade. No indexing for successive blades is required, but as the reamer revolves continuously, increments of each blade are successively ground as they pass the grinding wheel, each increment having the desired radial clearance.

Obviously, when the rod 15 is horizontal, the apparatus can be used to grind reamers having blades parallel to their axes, and by the use of suitable cams, it may be used for reamers having any number or spacing (regular or irregular) of blades.

While I have described the illustrated embodiment of my invention in some particularity, obviously many modifications and variations thereof will readily occur to those skilled in the art to which it appertains, and I do not, therefore, limit myself to the precise details illustrated and described, but claim as my invention all embodiments, variations, and modifications thereof coming within the scope of the subjoined claims.

I claim:

1. Feeding mechanism for a cutting machine having a rotating cutter and a table translatable axially past the same, which comprises a rotatable holder for an article being cut, a movable support therefor mounted on said table, means urging the support toward the cutter, a cam fixed to the holder to rotate therewith, a stop engaging the cam to

limit the movement of the support toward the cutter, and a support for said stop carried by a part of the machine stationary relative the cutter.

2. Feeding mechanism for a cutting machine having a rotating cutter and a work supporting table translatable with respect thereto, which comprises a rotatable work holder, a movable support therefor mounted on said table, resilient means urging the support toward the cutter, a cam carried by the holder to rotate therewith and limit the movement of the support toward the cutter, an arcuate guide carried by the table and stationary relative thereto, a roller interposable between the guide and cam to limit the movement of the support toward the cutter, and a roller support adjustably carrying the roller and carried by a part of the mechanism stationary relative the cutter.

3. Feeding mechanism for a cutting machine having a rotating cutter and a table translatable relative thereto, which comprises a rotatable holder for an article being cut, a movable support therefor mounted on said table, means urging the support toward the cutter, a cam carried by the holder to rotate therewith, an inclined adjustable stop engaging the cam to limit the movement of the support toward the cutter, an adjustable support for said stop pivotally carried by a stationary portion of the mechanism, and a stationary abutment for the stop carried by the table.

4. A fixture for use in conjunction with a grinding machine, which comprises trunnions attachable to the table of the grinding machine, a bed extending longitudinally of said table supported on said trunnions, supports on the bed for a multi-bladed cutter, resilient means rotating the bed about its trunnions toward the grinding wheel of the machine, a cam carried by the bed and rotated by the rotation of the supports, a stop carried by the grinding machine and engaged by the cam to limit the rotation of the bed toward the grinding wheel, the stop being angularly adjustable so that it contacts the cam in different horizontal planes as the table moves relative the grinding wheel.

5. A fixture for use on a grinding machine, which comprises trunnions attachable to the table of the machine, a bed extending longitudinally of the table and supported by the trunnions, supports carried by the bed for a multi-bladed cutter, resilient means rotating the bed toward the grinding wheel of the grinder, a cam carried and rotated by the support, a stop engaged by the cam to limit the rotation of the bed toward the grinding wheel, a support for the stop carried by the grinding machine and stationary relative the grinding wheel, the stop being angularly adjustable so that its position of contact with

the cam varies as the table moves relative thereto.

6. A fixture for use on grinding machines comprising trunnions attachable to the table of the grinding machine, a bed extending longitudinally of the table supported on said trunnions, supports on the bed for a multi-bladed cutter, resilient means for rotating the bed toward the grinding wheel of the grinder, a cam carried and rotated by rotation of the cutter, a fixed curved shoe carried by the table adjacent the cam, an angularly adjustable rod interposed between the cam and shoe and carried by a part of the grinding machine 10 stationary relative the grinding wheel.

15 7. A fixture comprising trunnions attachable to the reciprocating table of a grinding machine, a bed extending longitudinally of the table supported on said trunnions, a work 20 support on the bed, a cam rotated by rotation of the work, a fixed curved shoe carried by the table adjacent the cam, resilient means moving the bed toward the grinding wheel of the grinder and said shoe, a rod interposed between the cam and shoe and angularly adjustable 25 in a plane transverse to the radius of contact with the cam.

8. A fixture for use with grinding machines, comprising a bed adapted to be pivotally attached to the movable table of a 30 grinding machine, a headstock and a footstock carried by said bed, a cam rotated by the spindle of one of said stocks, a curved shoe carried by the table and stationary relative thereto, an angularly adjustable stop interposed 35 between said shoe and cam and carried by a part of the machine stationary relative the grinding wheel, and means for moving said table toward said shoe and grinding wheel.

40 9. A fixture for use with grinding machines, which comprises a bed adapted to be pivotally supported upon the movable table of a grinding machine, a headstock and a footstock supported by said bed, a spring moving said bed toward said grinding wheel, means 45 for rotating the spindle of the headstock, a cam carried by said spindle, a curved shoe carried by the table on the side adjacent the grinding wheel of the machine and adjacent said cam, and a rod interposed between the cam and shoe and adjustably carried by a support pivoted upon the bed of the grinding 50 machine.

55 In testimony whereof I hereunto affix my signature this 16th day of June, 1927.

PATRICK T. LENNON.
